FUZE

Parke H. Thompson, Kirkwood, Mo., assignor to
Amp Corporation, St. Louis, Mo., a corporation
of Missouri

Application October 4, 1945, Serial No. 620,291

8 Claims. (Cl. 102—74)

1

This invention relates to fuzes, and with regard to certain more specific features, to selective safety fuzes for projectiles.

The invention is an improvement upon that disclosed in my United States patent applications Serial No. 537,563, filed May 27, 1944, for Fuze, and Serial No. 592,131, filed May 5, 1945, for Fuze.

Among the several objects of the invention may be noted the provision of a reliable, point-initiated mechanical fuze which, prior to firing of a projectile, may easily be set for ultimate quick or delayed action upon impact; the provision of a fuze of the class described which is safe both before and after selective setting; and the provision of a fuze of the class described which is simple to manufacture in large numbers and in a large range of sizes. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a longitudinal section showing my new fuze in unarmed and unset position;

Fig. 2 is a lateral section taken on line 2—2 of Fig. 1;

Fig. 3 is a longitudinal and horizontal section taken on line 3—3 of Fig. 2;

Fig. 4 is an outside oblique view showing certain operating index characters;

Fig. 5 is a detail view of parts of Fig. 1 showing one selected setting for quick detonation;

Fig. 6 is a view similar to Fig. 5 showing another selected setting for delayed detonation;

Fig. 7 is a view similar to Fig. 1 but showing an armed condition for quick detonation;

Fig. 8 is a fragmentary detail view of parts of Fig. 7 but showing an armed condition for delayed detonation;

Fig. 9 is an enlarged detail section taken on line 9—9 of Fig. 3;

Fig. 10 is a section taken on line 10—10 of Fig. 9;

Fig. 11 is a detail cross section taken on line 11—11 of Fig. 10;

Fig. 12 is a detail cross section taken on line 12—12 of Fig. 10; and

2

Fig. 13 is a perspective detail view of a slide member.

Similar reference characters indicate corresponding parts throughout the several views of the drawings.

So far as is possible, reference characters will be used herein corresponding to those of said patent application Serial No. 592,131, in order that points of departure for the present invention may be noted more readily.

Referring now more particularly to Fig. 1, at numeral 1 is shown a tapered, inner fuze body having a threaded shank 3 for application to the threaded end of a projectile. The projectile 15 carries the main explosive charge to be detonated. It also carries the booster charge directly behind the shank 3. It is this booster charge that is exploded by means of the present fuze. The shank 3 is hollow and is interiorly threaded to receive a threaded retainer 5. This retainer has a spanner socket 7 with which a spanner wrench may cooperate for threading the retainer to its seat. Through the retainer is located a central passage 9 for transmitting to the booster 15 the detonating effect of the fuze. In the forward end of this passage 9 the retainer 5 is formed as a spherical seat 11 for seating a spherical safety rotor or gyroscopic element 13. The rotor 13 is carried for swiveling in a compartment 27, tapered at the front as shown at 29.

The rotor 13 has a bore 15 along an axis which passes through its spherical center. This bore by means of flanges at its ends, as shown at 17, retains two open detonator capsules 19 and 29. The capsule 19 may be referred to as a super-quick detonator and the capsule 29 as a delayed-action detonator. Capsule 19 (Fig. 9) contains an outwardly facing primer P—1 and an inwardly facing azide charge A. In the capsule 29 is an inwardly facing delayed-action charge D next to which is an ignitor charge I. Next to the ignitor charge and outermost is a primer P—2. The primers P—1 and P—2 are facing outwardly at the opposite openings O and O—1 in the rotor 13. The quick-action charge A and the delayed-action charge D face one another at inner openings O—2.

At 18 is shown a groove, limited in extent, which is located midway on a great circle between the ends of the axis of openings of bore 15. On another great circle through the ends of the axis of the bore 15 is a recess 21 which receives a tongue 22 of a selector key 23. This key 23 has a reduced flat end 22 and has a sliding fit in a bore 25 of a tumbler barrel 24. Tumbler

barrel 24 is rotatable in an angular bore 16 of the body 1. The bore 16 extends from the body 1 into communication with a larger opening 103 located in a conical cap 101. The latter fits over the body 1 and is held onto the body 1 by means of a conical cover 91 which is flanged as shown at 95. The flange 95 is gripped by an adjacent part of the projectile when the body 1 is screwed home. A lug 129 and socket 131 prevent rotation between bodies 1 and 101 (Figs. 2 and 3).

In regard to the cover 91, it will be seen that it tightly seals the fuze when the assembly is screwed home on a projectile, the flange 95 being squeezed tight. In order to prevent the cover 91 from rotating on the fuze before application, the body 101 is provided with an opening 125 into which a portion 127 of the cover is pressed. Thus a spanner wrench may be used at the resulting recess at 127 for applying the assembly to a projectile. It will be noted that the lug 129 on body 101 which cooperates with a recess 131 in the body part 1 prevents relative motion between the two.

The selector key 23 carries ears 84 which slide in grooves 85 of the tumbler 24. A spring 71 biases the key 23 in an inward direction to cause the tongue 22 to cooperate with the groove 21.

Outwardly the key 23 is provided with an extension 26 movable in an axial hole 28 of the tumbler barrel. This hole 28 ends in a flanged portion 105 of the tumbler barrel. This flanged portion 105 is crossed by a selector slot 107 which intersects the end of the hole 28. At right angles to the hole 28 is another hole 108 for an interlock tumbler 109. Through a hole 111 in the tumbler 109 passes a single-loop coil spring 113. The ends 115 of this spring abut on one side of the opening 103 (Fig. 11) and thus bias the interlock tumbler 109 therefrom. One end 115 is anchored in the hole 108, opposite the tumbler 109.

Tumbler 109 is biased toward a cam-forming recess 117 forming a ramification from the opening 103. This recess has three cam bights 119, 121 and 123. Bights 119 and 123 are symmetrical with respect to bight 121 and are radially deeper. Thus if the tumbler barrel 24 is turned to the central position shown in Figs. 10 and 11, the tumbler 109 will be pushed inward to its interlocked position against action of the spring 113. If the tumbler barrel 24 be turned there either clockwise or anticlockwise, the spring 113 will push the tumbler 109 either into the bight 119 or 123, thus withdrawing said tumbler 109 from its interlocked position of Figs. 10 and 11. The reason for this will appear.

The cover 91 is made of thin aluminum which covers the opening 103. At this point it is embossed or pressed thin within a circular bead 102 which serves as a locator for applying a screw driver or the like. Within the bead 102 the thin part is indicated generally at 104. It is thin enough easily to be broken by means of the setting tool but not thin enough that it will be easily broken in shipment. Across the central portion of this thin part or diaphragm 104 is formed a guide groove 106 which is parallel to the position of the slot 107 in the tumbler 24 when the latter is in the interlocked position of the tumbler 109 as shown in Figs. 10 and 11. Thus any flat tool which breaks through groove 106 automatically enters slot 107. The normal positions of groove 106 and slot 107 are crosswise of the axis of the projectile as a whole. For convenience, the index character "Off" is stamped opposite one end of the recess 106. This character means that

the fuze is set in an unarmed non-selective condition, as will appear. Next to the index character "Off" are the index characters "SQ" (meaning super-quick) and "Delay" (the meaning of which is obvious). These index characters "SQ" and "Delay" correspond to clockwise and anticlockwise release settings of the tumbler 109 in the bights 119 and 123 respectively, release being for possible radial movement of key 23.

10. From the above it will be clear that by applying a tool to the depression 106 and forcing it through, that it will enter the slot 107 for turning the tumbler 24 which in turn, through the slots 85 and ears 84, turns the key 23, including its tongue 22. This turns the ball rotor 13. Thus from one side this rotor may be turned either into an unarmed position for non-delay (quick) operation (Fig. 5), or an unarmed position for delay operation (Fig. 6). It will be evident that in all of the Figs. 1, 5 and 6 locations, the rotor 13 is in an unarmed condition.

When the key 23 is turned, since the axis of the safety sleeve 35 is not at right angles to the key, some component of rotation of the ball rotor 13 will occur with respect to the key in the Fig. 9 plane. Therefore the fit between the tongue 22 and the groove 18 is more or less loose as indicated in Fig. 10. This looseness does not interfere with the proper operation of the device, to be described.

30. It will be noted that if and when the projectile rotates at a substantial speed, centrifugal force will tend to drive out the key 23. If tumbler 109 is out of the way, resulting radial movement of the key may occur. This will free the ball rotor 13 for further movement as soon as another interlock, to be mentioned, opens. However, tumbler 109 will not free the key for retracting tongue 22 from rotor 13 until tumbler 24 is turned either to its "SQ" or its "Delay" position, that is, not until the fuze is prepared for firing.

Returning to the arcuate recess 18, it cooperates endwise with the beveled end of a safety sleeve 35. This safety sleeve slides in the rear cylindric part 37 of an axial bore 39 which enters the taper 29.

The front end of the safety sleeve 35 is approximately flush with the rear ends of two passages 41, each of square cross section. These slope rearwardly as indicated. Each carries a detent slide 43 of square cross section. The slides 43 include openings 31 through which are encircled a spiral arming spring 45 as shown in Fig. 2. This spring tends to bias the slides 43 inward.

55. It may be seen from Figs. 1 and 7 that the square openings 41 needed for the square slides 43 are provided simply by milling in the inner face of the member 101. At the end of the recesses 41 are openings 133 which extend through the skirt portions 135 of the bottom of body 101 where at the base it surrounds the body 1. These openings 133 accommodate outward movement of the slides 43. A circular open space 137 is left where the bodies 101 and 1 cooperate, for the reception of the circular spring 45.

A detail of each detent slide 43 is shown in Fig. 13. The inner end of each has a bearing portion 28 behind which is a semicircular groove 30. These inner end portions of the slide 43 are made for cooperation with a firing pin 53. This firing pin at the front end has a flat circular head 55 undercut as indicated at 57 to interlock with the grooves 30 in the slides 43. The rear end of the firing pin 53 is pointed as indicated at 59, the length of the pin being such that its point

under safety conditions lies within the safety sleeve 35 (Figs. 1 and 10). Thus the point 59 is normally completely protected from damage and, as will appear, does not release the rotor, this function being reserved for the safety sleeve 35.

The forward end 61 of the axial bore 39 is tapered outwardly toward the forward end of the projectile, the taper preferably starting at an enlarged portion 34 which accommodates motion of the firing pin head 55. The taper may, for example, be made .25 inch in diameter and tapered larger on the diameter .006 inch per inch of length passing forward.

Within the tapered bore 61 is a hollow striker 65, which is open at its rear adjacent to the head 55 and closed at its front end, as indicated at 67. With the rear end against the head 55, the front end 67 lies in the enlarged recess 63, but at some distance away from the outer edge 69 of said recess. The striker is relatively light, being hollow and made with thin walls. Since there is more metal at the closed end 67 than at the rear open end, the center of gravity of the striker 65 lies forwardly with respect to its central point along its length.

Operation is as follows: The fuze (mounted on the projectile) is received by the artilleryman in the condition shown in Figs. 1, 2, 9, 10, 11 and 12. This is its "Off" and safe condition for handling, being unarmed. Since the tumbler 109 locks in the key 23, no amount of mishandling prior to setting can release the rotor 13 from the tongue 22. Hence the rotor is positively held in the very safe Fig. 1 position until setting occurs.

To prepare the fuze for firing the artilleryman drives a tool such as a screw driver into the guide notch 106. This causes the screw driver to enter the slot 107 in the tumbler 24, this slot 107 at this time being parallel to the guide 106. If "super-quick" action at the end of the trajectory is desired, he turns the screw driver clockwise so as to move the tumbler 109 into the releasing cam lobe 119, thus withdrawing said tumbler from behind the extension 26. It will be seen that until this setting was made it would have been impossible under even high speeds of rotation of the fuze, or rough handling, for the key 23 to have been driven back. However, after making the stated setting, the tumbler 109 no longer interferes and under suitable rapid rotation of the fuze on its longitudinal axis key 23 may move out by centrifugal action against the spring 71, thus removing the tongue 22 from the slot 21. However, prior to rotation such removal does not occur. Hence the said setting to the "SQ" condition will merely turn the ball rotor 13 to the position shown in Fig. 5. The fuze under such conditions is still bore safe but it is now in condition to arm upon firing and consequent rotation. It is bore safe because one end of the groove 18 is locked by the safety sleeve 35. Hence the rotor can turn no further.

Had the operator decided to set the device to delayed action, he would, after having driven the screw driver through the groove 106, turned it anti-clockwise, which would have brought the tumbler 109 into the bight 123, thus again freeing the key 23 from the ball rotor 13 and setting the latter to the Fig. 6 angled position. Again, the ammunition would be bore safe because the other end of the groove 18 is locked by the safety sleeve 35.

Thus it will be clear that firing occurs under either the Fig. 5 or the Fig. 6 initial position

of the ball rotor 13, depending upon the initial setting which was made. From either of these Fig. 5 or Fig. 6 positions the rotor is adapted to move into its arming position when the ammunition is fired.

It will be noted that the motion from the Fig. 5 and Fig. 6 positions respectively to the Fig. 7 and Fig. 8 positions cannot occur until the safety sleeve 35 is moved out of the groove 18. This removal is effected after firing. Upon firing a set-back force is operative upon the rotor 13 which tends to seat it firmly upon the spherical seat 11. The safety sleeve 35 being set back positively continues to hold the rotor in a bore safe condition either as shown in Fig. 5 or as shown in Fig. 6. It is not the delicate point 59 of the firing pin 53 that holds the rotor, and the pin 59 is preserved in proper condition until needed. The set-back action of the strong safety sleeve 35 in holding the rotor 13 makes the fuze positively bore safe during the entire movement through the gun barrel. It also makes a rocket safe throughout the initial acceleration of its flight. It will also be noted that the rotor is held by the safety sleeve 35 in either the Fig. 5 or Fig. 6 position because, although spinning of the fuze tends to rotate the rotor clockwise in Fig. 5, and anti-clockwise in Fig. 6, neither of these rotations can occur as long as the safety sleeve 35 is in the circular groove 18.

In addition, set-back forces due to acceleration tend to send the striker 65 back against the head 55 of the firing pin, thus tending to lock said head into the groove 30 of the detent slides 43. This, in addition to the spring 45, and rearwardly sloping positions of the slides, tends for a certain period to hold in the slides. After the projectile has been angularly accelerated for a period, the resulting angular velocity reaches a point at which the spring 45 tends to expand and the detent slides 43 tend to move out. Then after linear acceleration ceases, linear deceleration sets in, due to unbalanced axial frictional forces exerted upon the projectile in passing through the air. Since there is no substantial frictional force on the striker 65, it, the firing pin 53 and the safety sleeve 35 tend to drift forward. This drift by itself may be indifferent. But, since the projectile is at this time spinning on its longitudinal axis at a substantial speed, and since the striker 65 has a conical spin in the conical bore 61, the striker positively moves forward against the impact diaphragm 93 and positively remains there as shown for example in Fig. 7. This action releases the slides 43 which move outward by centrifugal force. Thus they slide from in front of the firing pin 53 which also moves forward. Forward movement of the safety sleeve 35 also at this time locks out the slides so that they cannot again come in. This forward motion of the safety sleeve 35 also releases the ball rotor 13 so that the latter spins gyroscopically into a position coaxial with the openings 9 and 37. Which of the coaxial positions of Fig. 7 or 8 the rotor takes, depends upon the initial manual setting that was made either of Fig. 5 or Fig. 6.

When the target is reached, impact on the diaphragm 93 which is then in direct contact with the striker 65 drives the latter back with considerable force against the head 55 of the firing pin and drives it into the bore of the rotor 13. This explodes the detonator in this bore 15. The explosion is communicated through the

opening 9 to the booster charge which explodes the projectile charge.

If the rotor 13 comes into the armed position of Fig. 7, the quick-action detonator capsule 19 is forward. This explodes promptly and the resulting force blows through the delayed-action capsule 20 and into the booster charge. If, as in Fig. 8, the delayed-action capsule 20 is forward, it actuates with time delay. Thus it does not affect the capsule 19 for some period of time delay, but when capsule 20 does explode, the capsule 19 explodes into the opening 9 and activates the booster charge.

From the above it will be seen that there is provided a fuze having all of the safety features of the fuze of said application Serial No. 592,131. In addition, it may be set for either quick or delayed operation prior to firing, all with a construction which is almost as simple as that of said application Serial No. 592,131.

As to the action per se of the ball rotor 13, it is in effect a gyroscopic element which in the "Off" setting of the fuze is in a median position (Fig. 1), preferably at right angles to the axis of rotation of the projectile. Some deviation from right-angularity is not important. In either one of the set position ("SQ" or delayed) of this gyroscopic element such as shown in Figs. 5 and 6, it is conditioned to move clockwise or anticlockwise through an acute angle (less than 90°) when unlocked by the safety sleeve. When unlocked by this safety sleeve this gyroscopic rotor element 13 is free to precess either clockwise or anticlockwise respectively to its super-quick or delayed position coaxial with the axis of spin of the projectile such as shown in Figs. 7 and 8. In other words, it moves either from the Fig. 5 clockwise to the Fig. 7 position; or from the Fig. 6 position anticlockwise to the Fig. 8 position; all depending only upon which initial setting of Fig. 5 or Fig. 6 was chosen. Furthermore, this gyroscopic rotor element 13 is locked in its neutral position by the mechanism consisting of the key 23 and the interlocking tumbler 109 when the device is in its "Off" position.

As to the reason for the gyroscopic rotor action under projectile spin, this is due to the average density of the materials in the opening 15 being less than the density of the material of the rotor 13, which latter is for example made of commercial brass. This produces centroids in any section of the rotor on opposite sides of the axis of the bore 15. Hence when the projectile spins, as upon firing the ammunition, the rotor will spin, and the centroids will tend to seek a common plane of rotation perpendicular to the axis of spin. This will place the bore 15 of the rotor 13 coaxial with the bore 39 of the body 1 which is the desired arming position. The angular direction will always be such as to traverse the least (acute) angle, which accounts for the action above described.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A fuze comprising a body adapted to be spun upon a longitudinal axis, a gyroscopic rotor hav-

ing a gyroscopic axis, an adjusting means cooperating with said rotor to position it in either of two acute angular positions of said gyroscopic axis with respect to said longitudinal axis, said rotor under rotation of the body being adapted to precess in opposite directions from the respective alternate position into a position of said gyroscopic axis parallel with said longitudinal axis, and a detonating means carried by the rotor having oppositely positioned "quick" and "delayed" elements adapted to be reversely related on said longitudinal axis depending upon which position the rotor assumes upon said axis.

2. A fuze comprising a body adapted to be spun upon a longitudinal axis, a gyroscopic rotor having a gyroscopic axis, an adjusting means cooperating with said rotor to position it in either of two acute-angle positions of said gyroscopic axis with respect to said longitudinal axis, said rotor under rotation of the body being adapted to precess from the respective alternate position over one of the acute angles into a position of said gyroscopic axis parallel with said longitudinal axis, a detonating means carried by the rotor having oppositely positioned "quick" and "delayed" elements adapted to be reversely related on said longitudinal axis depending upon which position the rotor assumes upon said axis, and means responsive to spin of the body adapted to release the adjusting means from cooperative relation to the rotor so that the rotor may precess freely.

3. A fuze for projectiles comprising a body adapted to be spun upon a longitudinal axis, a gyroscopic rotor normally positioned with its gyroscopic axis in a median position at an angle with respect to said longitudinal axis, an adjusting locking key cooperating with said rotor to position it in said median position or in either of two other alternate angular positions of the gyroscopic axis with respect to the longitudinal axis, a safety member movable parallel to said longitudinal axis in response to linear deceleration of said body, means on said rotor cooperating with said safety member adapted in either of said alternate positions and before movement of the safety member to lock the rotor, said rotor under rotation of the body being adapted when released by the safety member to precess in either of opposite directions from the respective alternate position into a position of said gyroscopic axis parallel with said longitudinal axis, and means for mounting said key so that when said body is spun it may move from a cooperating position with respect to the rotor provided that the key has set the rotor to one of said alternate angular positions.

4. A fuze for projectiles comprising a body adapted to be spun upon a longitudinal axis, a gyroscopic rotor normally positioned with its gyroscopic axis in a median position at an angle with respect to said longitudinal axis, an adjusting locking key cooperating with said rotor to locate it in said median position or in either of two other angular positions of said gyroscopic axis with respect to said longitudinal axis, a safety member movable parallel to said longitudinal axis in response to linear deceleration of said body, means on said rotor cooperating with said safety member adapted in either of said alternate positions to lock the rotor before movement of said safety member, said rotor under rotation of the body being adapted to precess in either of opposite directions from the respective

alternate positions into a position of said gyroscopic axis parallel with said longitudinal axis, means for mounting said key so that it may move from a cooperating position with respect to the rotor when said body is spun, and interlock means for preventing said movement of the key when it is in a position corresponding to a setting of said rotor in said median position.

5. A fuze for projectiles comprising a body adapted to be spun upon a longitudinal axis, a gyroscopic rotor normally positioned with its gyroscopic axis in a median position at an angle with respect to said longitudinal axis, an adjusting key cooperating with said rotor to position it in either of two other alternate angular positions of said gyroscopic axis with respect to said longitudinal axis, a safety member movable parallel to said longitudinal axis in response to linear deceleration of said body, means on said rotor cooperating with said safety member adapted in either of said alternate positions to lock the rotor therein before movement of said safety member, said rotor under rotation of the body tending to precess in either of opposite directions from the respective alternate position into a position of said gyroscopic axis parallel with said longitudinal axis, and a detonating means carried by the rotor having oppositely positioned "quick" and "delayed" elements adapted to be reversely related on said longitudinal axis depending upon which position the rotor assumes upon said axis.

6. A fuze comprising a gyroscopic rotor adapted to be set into a median or either of two alternative positions, means for setting said rotor comprising a slot therein, a rotary tumbler barrel, a slideable key in said barrel, said key having a tongue and being biased for cooperation between said tongue and said slot, a tumbler pin in the tumbler barrel, and cam means traversed relatively by said tumbler pin upon relative rotation between the tumbler barrel and the cam means to prevent movement of the key with its tongue from said slot in the median position of the rotor but in said alternative positions of the rotor permitting movement under centrifugal force of the key and its tongue from said slot.

7. A fuze comprising a body having a longitudinal axis of spin, an opening along said axis, a firing element operative along said opening, a gyroscopic rotor in said opening, said rotor having a gyroscopic axis, an opening in said rotor along said gyroscopic axis, detonating means in said rotor opening presenting a fast-acting component toward one end of the opening and a slow-acting component toward the other end thereof, selector means for setting said gyroscopic axis angularly with respect to said longitudinal axis on either of opposite sides of a median plane substantially normal to the longi-

tudinal axis or in said median plane, whereby upon spin of said body the gyroscopic rotor will precess in either one of opposite acute-angle directions to set either the slow-acting detonator component or the fast-acting detonator component along the longitudinal axis in the direction of said firing means, said selector means comprising a centrifugally retractable key normally cooperating with the rotor, means for adjusting the key, and interlock means preventing centrifugal retraction of the key in the position of the rotor with its axis in said median plane but permitting retraction of the key in the position of the rotor with its axis in either one of said two angular positions.

8. A fuze comprising a body having a longitudinal axis of spin, an opening along said axis, a firing element operative along said opening, a gyroscopic rotor in said opening, said rotor having a gyroscopic axis, an opening in said rotor along said gyroscopic axis, detonating means in said rotor opening presenting a fast-acting component toward one end of the opening and a slow-acting component toward the other end thereof, selector means for setting said gyroscopic axis angularly with respect to said longitudinal axis on either of opposite sides of a median plane substantially normal to the longitudinal axis or in said median plane, whereby upon spin of said body the gyroscopic rotor will precess in either one of opposite acute-angle directions to place either the slow-acting component or the fast-acting component along the longitudinal axis in the direction of said firing means, said selector means comprising a centrifugally retractable key normally cooperating with the rotor, means for adjusting the key, interlock means preventing centrifugal retraction of the key in the position of the rotor with its axis in said median plane but permitting retraction of the key in the position of the rotor with its axis in either one of said two angular positions, and further interlock means cooperating with the rotor to hold it in either one of its angular positions until the body has passed through a period of linear and angular acceleration and subsequent linear deceleration.
